DESIGN FOR A CARPET.

SPECIFICATION forming part of Design No. 15,854, dated February 24, 1885.

Application filed January 14, 1885. Term of patent 3½ years.

To all whom it may concern:

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

The face of the design shows several prominent flower and leaf groups interblent with rectangular and scroll-like panel-work and small geometric work, all as clearly shown in the photograph.

I claim—
